(57) CLAIM

The ornamental design for a light fixture with a finial, as shown and described.

DESCRIPTION

FIG. 1 is a top plan view of a light fixture with a finial showing my design;

FIG. 2 is a bottom plan view thereof; and,

FIG. 3 is a side elevation view thereof.

Due to the symmetric nature of the design, the left, right, front and back sides of the light fixture with a finial are identical, and, thus, only one view is shown herein.
